Attorneys

UNITED STATES PATENT OFFICE.

FRANK E. McDOWELL, OF LOUISVILLE, KENTUCKY.

DESIGN FOR A TOY.

60,799.

Specification for Design. Patented Apr. 11, 1922.

Application filed April 18, 1921. Serial No. 462,443. Term of patent 3½ years.

To all whom it may concern:

Be it known that I, FRANK E. McDOWELL, a citizen of the United States, residing at Louisville in the county of Jefferson and State of Kentucky, have invented a new, original, and ornamental Design for a Toy, of which the following is a specification, reference being had to the accompanying drawing, forming part thereof. The figure is a perspective view of a toy showing my new design.

I claim:

The ornamental design for a toy, as shown.
FRANK E. McDOWELL.
